UNITED STATES PATENT OFFICE.

HENRY H. WAIT, OF CHICAGO, ILLINOIS.

DYNAMO-ELECTRIC MACHINE.

1,399,832.

Specification of Letters Patent. Patented Dec. 13, 1921.

Application filed August 23, 1917. Serial No. 187,782.

To all whom it may concern:

Be it known that I, HENRY H. WAIT, a citizen of the United States, residing at Chicago, in the county of Cook and State of Illinois, have invented a certain new and useful Improvement in Dynamo-Electric Machines, of which the following is a full, clear, concise, and exact description.

My invention relates to dynamo electric machines and has for one of its objects the simplification of means for lessening the noise occasioned by rotating armatures.

My invention also has for its object an improvement in the ventilating arrangement of the armature to improve the circulation of armature cooling air. The preferred way of achieving the second object of my invention also lessens the noise produced by the tangs, but I do not limit myself to this added advantage.

In carrying out the first object of my invention I afford an air inlet adjacent the armature tangs from which the air flows to the tangs and ultimately along the tangs in outward directions so that the air and tangs are rotating at substantially the same velocity at the outer ends of the tangs where the cooling air leaves the armature and where the greatest noise is likely to occur. The air enters at places where the speed is relatively low to reduce the noise at the places of entry, velocity being increasingly imparted to the outwardly moving air until it is substantially that of the tangs where the air leaves them.

In carrying out the second object of my invention I subdivide the armature into zones with ventilating spaces between, through which armature cooling air finds its way. Air distributing channels are provided with air distributing portions near the axis of the armature for effecting circulation of cooling air through said spaces. The end of each channel adjacent the commutator is sufficiently closed to prevent the commutator tangs from acting as a centrifugal fan to suck a material quantity of the air directly through the channels and divert it away from the ventilating spaces. In preventing this action of the commutator tangs upon the air flowing through said

channels, I eliminate the noise that the action of the tangs upon this air would occasion.

I will explain my invention more fully by reference to the accompanying drawings showing the preferred embodiments thereof and in which Figure 1 is a longitudinal view, partially in section and partially in elevation of a dynamo electric machine constructed in accordance with the invention; Fig. 2 is a view on line 2-2 of Fig. 1; Fig. 3 is a detail view, somewhat diagrammatic of the structure illustrated in Fig. 1 and Fig. 4 is a detail view in transverse section.

Like parts are indicated by similar characters of reference throughout in both figures.

The dynamo electric machine illustrated has a field portion not shown which is inclusive of a field ring, radial pole pieces carried by and projecting inwardly from the ring, and field coils. The armature 4 is carried upon a shaft 5 which turns within bearings 6 that are supported by standards 7 upon a base 8. The dynamo electric machine shown is one which operates at a high rate of speed, on which account its commutator 9 is surrounded by annular steel bands 10 (suitably insulated from the commutator) and serving to prevent the commutator bars from being dislodged or misshapen through the action of centrifugal force. The commutator brushes 11 (of which only one 11 is illustrated in Fig. 2) are disposed upon studs 12 which are anchored at their inner ends to an annular carrier 13 and at their outer ends to an annular carrier 14. These annular carriers 13 and 14 are desirably respectively disposed in the planes of rotation of the inner and outer steel bands 10. The two outer bands 10 and the adjacent bearing 6, together with its supporting standard 7, prevent mere endwise displacement or removal of the carriers 13 and 14 and the brushes 11 carried thereby, on which account I form the carriers in sections that meet on diametrical lines of the carriers. When the carriers are thus formed in split sections, providing they are suitably mounted, they may readily be withdrawn from the machine by a movement thereof.

in the plane of rotation of the commutator, a result which may be effected without disturbing individual adjustments of the commutator brushes 11. The brush structure 5 that includes the carriers 13 and 14, the studs 12 and the brushes 11 upon said studs, is mounted to rotate upon an axis coincident with the axis of the shaft 5. The mounting is preferably double, there being a mounting 10 15 for and concentric with the carrier 13 and a mounting 16 for and concentric with the carrier 14. The carrier 15 is mounted upon the base 8 rather than upon any portion of the dynamo electric machine itself. By dividing the mounting structure into two separate mountings 15 and 16 the outer mounting 16 may be made of iron, while the inner mounting may be made of non-magnetic material for the purpose which has been stated. 20 The mountings 15 and 16 are desirably segmental, the engagement thereof with the rings 13 and 14 being limited to arcal portions of these rings 13 and 14 that are not in excess of 180°. The carrier rings 13 and 25 14 are rotatable in the mountings 15 and 16 to enable the entire structure to be turned in adjusting the position of the brushes with respect to the axis of commutation.

Whether the other surfaces of the carrier 30 rings are smooth or not, the carrier ring 13 is practically smooth on the side toward the commutator tangs 17. This carrier ring, in combination with the rings and supporting drum of the armature, forms a chamber resembling the casing and diffuser of a centrifugal fan. The ring 13, being located close to the tangs 17, prevents these tangs from cutting through the stationary surrounding air. The air enters the space between ring 13 and the armature through the slight annular space 18 that intervenes between the ring 13 and the band 10 that is in the plane of and surrounded by ring 13. The portions of the commutator tangs where 40 the air inlet is located run at a relatively lower speed. The tangs impart an increasing velocity to the air passing outwardly along the tangs, the velocity of the tangs and air being substantially equal at the periphery of the body of tangs, where the air leaves the armature, whereby noise is eliminated or materially reduced at this locality where there is usually loud noise.

By this arrangement, I have reduced the 50 windage loss of a machine two or three kilowatts, an increase of two or three per cent. in efficiency in machines of the kind illustrated, a result which is obtained without inclosing the machine and preferably by the use of a ring that performs the additional function of carrying commutator studs.

Noise has been further reduced by my improved ventilating construction. The armature is provided with longitudinal ventilating channels 19 located near the axis of

rotation and in communication with transverse ventilating spaces 20. The ends of the channels 19 adjacent the commutator are completely or sufficiently closed by plugs 21 to prevent the commutator tangs, that act 70 as a centrifugal fan and very forcefully at high speed, from sucking the bulk of the air passing through said channels directly out of the channels themselves and shunting the cooling air that would otherwise be 75 free for passage through the ventilating spaces 20. The spacers 22 in the spaces 20 form fans that furnish just enough air to cool the core, etc., excess of air being prevented from getting to the commutator tangs either through the armature or at the ends. Enough air is thus blown without any useless excess that would waste power 80 and be productive of noise.

Having thus described my invention, I 85 claim as new and desire to secure by Letters Patent the following:—

1. A dynamo electric machine, including its armature, commutator, commutator bands, and commutator tangs; in combination with a ring adjacent and facing the commutator end of the armature and surrounding a commutator band, said ring forming with the adjacent portion of the armature a chamber, there being an air passage into said chamber between the ring and the commutator band surrounded by the ring and nearer the axis of the armature than the periphery of the body of tangs; and a commutator brush structure of which 95 100 said ring forms a part.

2. A dynamo electric machine including its armature and commutator, said armature having transverse ventilating spaces and longitudinal air channels in communication 105 with said ventilating spaces; commutator tangs at the inner end of the commutator; and plugs entering the inner ends of said longitudinal air channels.

3. In a dynamo electric machine, the combination with an armature provided with windings; of a commutator provided with tangs connected to said windings; a shield ring axially adjacent said tangs on the outside and extending radially beyond them; and a second ring axially adjacent said tangs on the inside and extending radially beyond them. 110 115

4. In a dynamo electric machine, the combination with an armature provided with windings; of a commutator provided with tangs connected to said windings; a shield ring axially adjacent said tangs on the outside and extending radially beyond them; and a second ring axially adjacent said tangs on the inside and extending radially beyond them, said rings forming a diffusion 120 125 passage outside the tips of said tangs.

5. In a dynamo electric machine, the combination with a laminated armature core; 130

of windings on said core; a commutator; tangs connecting said commutator and said windings; there being ventilating passages in said armature core and other ventilating passages adjacent said commutator tangs; and separate means for adjusting the area of communication between said core ventilating

5

passages and said commutator ventilating passages.

In witness whereof, I hereunto subscribe 10
my name this 22nd day of August, A. D.,
1917.

HENRY H. WAIT.
